UNITED STATES PATENT OFFICE.

FREDERICK C. ODELL, OF LYNN, MASSACHUSETTS, ASSIGNOR TO HARRY H. HANCOCK,
OF SWAMPSCOTT, MASSACHUSETTS.

RECEPTACLE.

1,162,389.

Specification of Letters Patent. Patented Nov. 30, 1915.

Application filed March 24, 1914, Serial No. 826,836. Renewed February 16, 1915. Serial No. 8,630.

To all whom it may concern:

Be it known that I, FREDERICK C. ODELL, a citizen of the United States, residing at Lynn, county of Essex, and State of Massachusetts, have invented certain new and useful Improvements in Receptacles, of which the following is a specification.

This invention relates to receptacles, as for instance waste-paper baskets, and the general objects of the invention are to provide a practical, efficient and simple receptacle or container.

These being among the general objects of the invention, the same consists of certain features of construction and combinations of parts to be hereinafter described and then claimed with reference to the accompanying drawings illustrating a suitable embodiment of the invention, and in which—

20 Figure 1 is a front elevation of my improved receptacle showing the same in collapsed or folded position, parts being indicated in dotted lines; Fig. 2 is an enlarged vertical section on the line 2—2 Fig. 1; Fig. 25 3 is an underside view of the improved receptacle when opened out for use; and Fig. 4 is a section on the line 4—4 Fig. 3, a portion of the body being broken away.

Referring to the drawings, the body 10, 30 11, of the receptacle may be of any suitable construction and of any suitable material, but it is preferably made of pasteboard. Each of the parts 10, 11, of the body are preferably made complementary to each other so that they can be cut out by the same die. They are shown as composed of a plurality of sections and they are connected together in suitable manner at opposite edges by means of rivets or fastenings 12, 13. To 35 enable the body to be collapsed or folded and to be extended so as to provide an encircling or containing body, the sections of the body are made to fold together which is usually done by scoring the body vertically 40 as at 10^a.

Whatever may be the construction of the body of the receptacle, the improvement of the present invention resides in the means for closing one end of said body. As shown 45 in the drawings, the construction is the following: A closure member or plate 14 is provided with a fold joint at 15 located adjacent one side of the body 10, 11, and below said fold joint is an extension 16, which is 50 fastened to the body as by means of rivets

17, 18. This closure member 14 and its said parts are also usually made of pasteboard, and the fold joint at 15 is made by scoring the piece of which said closure member 14 forms a part. Below the closure member 14 55 there is located a movable support, brace or distending member 19, 20, which is provided at opposite edges with downturned extensions 21, 22, which are secured to diametrically opposite parts of the body 10, 11, as 60 by means of the said rivets 17, 18, and by means of an additional rivet 23. The sections 19, 20 and their described parts are preferably made of pasteboard, and the opposite ends of the pasteboard are scored 65 transversely as at 24 and 25 so as to provide fold joints, and intermediately of the joints 24, 25 it is scored transversely at 26. It will be seen that the area of the closure member 14 and the combined area of the sections 19 70 75 and 20 of the support, brace or distending member corresponds substantially with each other.

Receptacles constructed substantially as set forth may be flattened out or collapsed 80 so as to occupy a small compass, for storing away or for transportation. To open it out, one hand is inserted within the body and pressure is brought to bear upon the closure member 14 which not only moves said member to closing position but also acts to spread out or distend the sections 19, 20, so that when the parts are in open using position, said sections 19, 20 will be substantially parallel with the closure member 14 so as to 90 properly support the same and to hold the body 10 distended. To fold or collapse the receptacle, it is only necessary to press one hand against the fold joint at 26, thereby folding the sections 19 and 20 and the closure member 14 together, within the collapsed body 10, as shown in Fig. 2.

It is obvious that this invention is susceptible of a wide range of modification, as parts may be modified, parts omitted, and parts added and substituted without departing from the general nature of the invention.

What I claim as new is:—

1. In a device of the character described, 105 the combination of a body providing the side walls of said device, a support attached to opposite sides of said body and constructed to fold within said body, and a closure member having an area which is substan-

tially that of the inclosed area of said body to be supported by said support.

2. In a device of the character described, the combination of a body providing the 5 side walls of said device, a support hinged to said body at both ends and having an intermediate fold joint, said support being foldable within said body, and a closure member to be supported by said support.

10 3. In a device of the character described, the combination of a body providing the side walls of said device, a support hinged to said body, and a closure member to be supported by said support, said support and 15 closure members having approximately the same area, which area is substantially that of the inclosed area of said body.

4. In a device of the character described, the combination of a flexible body, providing 20 the side walls of said device, a distending member for said body having an intermediate fold joint so that it is foldable into said body, and a closure member supported above and adjacent said distending member.

25 5. A closure for a receptacle comprising an intermediately folding brace and a flap or plate member foldable against said brace, said parts having an edge connection, and fold joints adjacent said edge connection, all 30 of said folds being parallel.

6. A closure for a receptacle comprising an intermediately folding brace and a flap or plate member foldable against said brace, said parts having an edge connection and 35 being of approximately the same area, and fold joints adjacent said edge connection, all of said folds being parallel.

7. In a device of the character described, the combination of a collapsible body comprising 40 folding sections, a distending member having an intermediate fold joint and hinged at opposite edges to opposite sections of said body so as to fold within said body, and a closure member supported by said distending member.

45 8. In a device of the character described, the combination of a flexible body, an inwardly collapsible member of flat material connected at opposite edges with said body

and having an area substantially that of the 50 inclosed area of said body when the latter is extended, and a closure member supported by said collapsible member.

9. In a device of the character described, the combination of a collapsible body, a 55 closure member hinged at one edge at one side of said body, and a distending member hinged at the opposite side of said body, and also hinged on a line adjacent and parallel with a diameter of said closure 60 member, so as to have a coöperating relationship with said closure member.

10. In a device of the character described, the combination of a collapsible body comprising folding sections, a distending member 65 in the bottom thereof, comprising two sections having downturned extensions secured to the inner surfaces of opposite sections of said body, the said sections of said member having hinge connection with the 70 upper parts of said extensions, whereby said member is positioned above the lower ends of said folding sections, and an inwardly acting connection for said distending-member sections, said distending member 75 being thereby collapsible into said body when said body is collapsed.

11. In a device of the character described, the combination of a collapsible body comprising folding sections, a distending member 80 in the bottom thereof, comprising two sections having downturned extensions secured to the inner surfaces of opposite sections of said body, the said sections of said member having hinge connection with the 85 upper parts of said extensions, whereby said member is positioned above the lower ends of said folding sections, said distending-member sections having a dimension greater 90 than the running length of said hinge connection, and an inwardly acting connection for said distending-member sections, said distending member being thereby collapsible into said body when said body is collapsed.

FREDERICK C. ODELL.
